UNITED STATES PATENT OFFICE.

WALTER T. KRAUSCH, OF LA GRANGE, ILLINOIS.

STORAGE STRUCTURE.

1,356,155.

Specification of Letters Patent. Patented Oct. 19, 1920.

Application filed March 29, 1918. Serial No. 225,414.

To all whom it may concern:

Be it known that I, WALTER T. KRAUSCH, a citizen of the United States, and a resident of La Grange, in the county of Cook and 5 State of Illinois, have invented a certain new and useful Improvement in Storage Structures, of which the following is a description, reference being had to the accompanying drawings, which form a part of my 10 specification.

My invention relates more particularly to coaling stations of the type quite generally employed by railroad systems at various points, which enable the locomotive tender to 15 be readily charged or supplied with fuel or coal; the invention relating more especially to the construction of the coal hopper or storage compartment, namely the chamber or bin of the station wherein a considerable 20 quantity of coal is temporarily stored, and from which the coal is delivered into the locomotive tender.

The invention is also adaptable to stations or structures where sand, ashes and other 25 similar material is to be stored, which necessitates the provision of bins or chambers, the walls whereof are subjected to excessive wear or usage as the result of the character and handling of the temporarily stored material; 30 the walls heretofore having been constructed of wood with sheet metal lining, or entirely of metal, and therefore at great initial cost.

The object of my invention is to provide 35 a construction which will eliminate the difficulties and losses that are constantly encountered by the various railroad systems with the present day type of coaling station, and especially in regions or localities where the class of fuel or coal obtainable is of such a 40 combustible nature that its storage for a comparatively short period of time in a chamber or hopper frequently results in fires due to spontaneous combustion. It has been found in practice, that certain types of coal, 45 as for example lignite, have caused considerable loss through fire, by reason of the highly volatile character of the coal.

In order to overcome, or rather to somewhat eliminate, the loss that have been encountered by railroad systems, as a result of 50 fires originating as above mentioned, resort has been made to the use of sheet metal as a lining for the hoppers or bins in order to reduce, as much as possible, the difficulty referred to.

Such practice, however, is not only ex-

tremely expensive, due to the high cost of the sheet metal, but also necessitates care being exercised in the provision of proper joints or suitable overlapping connections 60 between the various metal sheets, to obviate the possibility of the studding or wooden framework of the station becoming ignited. As is readily apparent, such practice, aside from the cost of the steel sheeting, is also 65 very expensive in installation by reason of the time and labor involved, which is not only required in the initial installation of the metallic lining, but also in the repeated renewal thereof, due to wear caused by the 70 constant shifting or movement of the coal supply, or other material, in its passage through the hopper, from the loading or filling chute to the outlet or discharging chute.

The object of my invention is to construct 75 the storage bins or chambers of a coaling station, or storage structure, of a plurality of structural units consisting of reinforced concrete planks or slabs of such formation and nature as will enable their being easily 80 handled and quickly put into place and secured to the studding or other structural members so as to constitute the walls of the bins or hoppers, adapted to not only withstand the wear and strains, but which will 85 also not be affected by heat, because of the non-inflammable nature of the structural units which constitute the inner walls of the bins or chambers.

The further object of my invention is to 90 provide structural units in the nature of reinforced concrete slabs or planks, for constructing the storage bins or chambers; the structural units being previously molded 95 into transportable planks or slabs of suitable dimensions which are adapted for use in connection with the usual wooden uprights or posts and structural or supporting frame elements also usually formed of wood; the invention contemplating the use of indestructible slabs or planks which, like the structural supporting elements, will be 100 transportable from place to place, and which at the same time will greatly enhance the life of the stations or structures and also 105 materially reduce the initial as well as the up-keep cost thereof.

The invention and its advantages will be readily comprehended from the following description of the accompanying drawings, 110 wherein:—

Figure 1 is a side and end elevation of a

coaling station, in perspective, with portions broken away, in order to more clearly disclose the internal or bin construction.

Fig. 2 is a detail view, in longitudinal section, of one form of my improved structural unit.

Fig. 3 is a detail view, in perspective, of a wall section showing a modified form of structural unit and a method of installation.

Fig. 4 is a similar view disclosing another modified form.

My invention contemplates the provision of storage structures of the nature hereinbefore referred to formed in the most inexpensive manner, that is of the most inexpensive material, and wherein the various structural elements thereof may be renewed from time to time; the wear-receiving elements or units of the structure being formed of concrete planks or slabs in transportable form, so that the structure may be moved to a different location; my improved structure therefore possessing the advantages of a concrete construction without, however, incurring the expense and disadvantages of a monolithic structure.

My invention being especially adapted for use in the construction of coaling stations employed along railroad right-of-ways, its application to such stations has been chosen as an exemplification.

As the general construction of the coaling stations,—to-wit: the coal hoist, charging chute disposed intermediate of the hoist-shaft or tower and the bin or hopper, and general arrangement of sand-tank and adjacently placed bins or hoppers, as illustrated in the drawings—is of a well known type at present employed by railroad systems, and forms no part of my invention, an elaborate detailed description of the coaling station construction and arrangement will not be entered into, except to an extent sufficient to enable a clear understanding or comprehension of the invention being had.

In the particular exemplification, the station is illustrated provided with the usual hoist-tower or shaft at 10, in which suitable means are arranged for elevating the coal from cars, or other suitable sources of supply, adjacent the bottom of the shaft to the top of the station,—namely to a point preferably somewhat above the coal-storing bin or hopper, indicated at 11,—where the lift or elevating means is induced to discharge its supply into a suitable chute, indicated at 12, whereby the coal is directed into the bin or hopper 11. In practice, coaling stations are often provided with a plurality of storage bins or hoppers, which are preferably arranged side by side, with the hoist-shaft 10 and the chute 12 arranged so as to enable the coal to be discharged toward either side of the median line or vertical

axis of the hoist-shaft and into the selected bin or hopper; and for that reason the chute 12 is usually tiltably mounted to permit it to be swung to either side of its pivotal point and thus direct the coal into bins located on opposite sides of the vertical plane of the pivotal point or axis of oscillation of the chute.

The coaling station proper, as well as the hoist-shaft or tower, is usually constructed of wood; timbers and studding of suitable sizes and number being employed to provide the desired strength and rigidity to maintain the weight of the fuel and material stored in the station and to withstand the wear to which it is subjected. The tiltable member or chute 12 is usually constructed of wood and provided with a lining of sheet steel. The storage bin or hopper 11 is generally provided with a sloping bottom, as indicated at 13, with the bottom sloping downwardly toward one side of the station, namely the track side thereof, where the locomotive and its tender are placed and charged; suitable means being provided at the discharge opening or outlet of the hopper or bin for controlling the outflow of coal and also to direct it properly into the tender of the locomotive.

As previously stated, the present practice employed is to construct the side, top and bottom walls of the hopper or bin of wooden planks or boards properly secured to the studding, and then cover the interior, or rather the wooden planks or boards with sheet steel. This practice, however, is not only very expensive, due to the cost of the material, and the time and labor required in the initial installation thereof, but also in the maintenance thereof.

With my invention, the initial cost, as well as the cost of maintenance, will be materially reduced and considerable time and labor saved, as I propose to construct the bin or hopper of fireproof units in the nature of concrete planks or slabs of suitable dimensions, reinforced so as to withstand the wear and strains to which they are subjected. As disclosed in Fig. 1, the concrete planks, indicated at 14, are preferably arranged in juxtaposition, to extend laterally across adjacently set studding and supporting frame members, with the concrete units in close fitting relation with one another so as to provide suitable joints.

The construction of the units or slabs is shown in detail in Fig. 2, and consists of concrete molded into predetermined plank lengths and widths which enable the easy handling thereof, and at the same time of sufficient thickness. The units disclosed in Figs. 1 and 2 are preferably provided with a plurality of spacing bars or metallic members, the ends whereof are preferably bent substantially at right angles to the main

portion, with all of the ends disposed in the same direction, so as to provide the somewhat U-shape formation, as shown at 15 in Fig. 2. These spacing members or bars 15 may consist of suitable iron rods preferably arranged with their bent ends in abutting relation, as shown in Fig. 2, and preferably so embedded in the concrete that the ends will come flush with one side of the plank, as shown. The number of spacing members employed would be governed by the dimensions of the plank it is desired to form. The length of the respective spacing members or bars 15 may substantially correspond with or be slightly greater than the distance intervening the studding 16 (shown in Fig. 1), so as to bridge the space between the studding. If the plank is not of too great a width, then a single series or row of spacing bars 15 may be employed, preferably arranged substantially coincident with the longitudinal center line of the plank. With the planks arranged laterally in the bin or hopper, it is apparent that where the reinforcing members 15 are arranged, as above described, the out-turned ends of the reinforcing members or spacing bars 15 will be disposed in abutting relation with the adjacently placed studding 16. In addition to the reinforcing members or spacing bars 15, I prefer to provide each plank with reinforcing metallic bars 17 arranged transversely of the plank, namely at right angles to members 15; these reinforcing bars 17 being maintained in their spaced relation, during the molding of the plank, by the reinforcing elements or spacer-bars 15; the reinforcing bars 17 being preferably disposed in the groove or channel formed by the turned ends of the adjacent spacing members 15, as clearly disclosed in Fig. 2. It is clearly apparent from the construction shown and described, that the plank is thus reinforced both longitudinally and laterally, thus adapting it to withstand the considerable strains and impacts to which it is subjected.

The planks may be maintained in place against the studding of the bin or hopper 50 of the station by any suitable means, as for example by lag-screws or bolts, indicated at 18. If desired, perforated metallic plates or washers, as at 19, may be employed in conjunction with the lag-screws or bolts, in order to provide sufficient purchase on the concrete plank.

In Fig. 3 I illustrate a modified form of my improved structural unit shown in the form of a reinforced concrete plank or slab 60 which is reinforced by the embedded wire mesh shown at 20 of a well known construction, with the longitudinal edges of the different units being beveled as shown at 21, so that self-setting or self-forming joints between the respective superimposed units

may be formed, which are also of moisture shedding nature; the bevel of the respective units being so arranged that the slabs or plank 22 tend to remain in close relation with the supporting members or studding 70 16. The units, like those described in connection with Figs. 1 and 2, are intended to be molded into slabs or planks of such dimensions of length, width and thickness, that they may be readily transported from place to place and adapted to withstand the wear to which they are to be subjected; the units being secured to the frame members or studding in any suitable manner, as for example by suitable screws or bolts, as shown 80 at 23.

In Fig. 4, I show another modified form of the structural units 24 which, like the units 22 in Fig. 3 and 14 in Figs. 1 and 2, are intended to be composed of concrete and provided with a reinforcing element, as at 20, embedded therein in a manner similar to that disclosed in Fig. 3. The units 24 have their longitudinal edges provided with a double bevel, so as to provide an interlocking 90 connection between the respective units and an interlocking moisture-proof connection; the one longitudinal edge of each slab or plank being beveled outwardly so as to provide the protruding apex portion, as shown at 25, 95 while the opposite longitudinal edge of each plank or slab is beveled inwardly so as to provide a groove, as shown at 26, adapted to receive the correlated portion or projection 25 of the adjacent unit or slab. 100

The units may be secured to the frame members or studding 16 in any suitable manner; being shown secured in place by means of the screw bolts 23.

In the event that a portion of the inner 105 wall of the storage chamber need be renewed, because of undue wear, it is evident that this may be accomplished by simply replacing the respective unit or units, and those immediately about them, if the constructions shown in Figs. 3 and 4 are employed, without necessitating a complete dismantling of the structure.

With the storage bin or hopper constructed as herein described, it is evident 115 that a substantially indestructible construction is provided, whereby the difficulties heretofore encountered will be entirely eliminated; and yet at the same time, a construction is provided which may be taken down and transported without destroying the structural units which constitute the storage chambers and thereby permitting their reuse, thus obviating the necessity of the complete demolition of the storage structure as 120 would be the case where a monolithic concrete structure had been constructed; and while the construction shown and described is believed to be the best adaptation of the 125 invention, alterations might be made in cer- 130

tain respects without departing from the spirit of my invention.

What I claim is:—

1. A coaling station provided with a hopper or bin, comprising a supporting structure composed of wooden frame members spaced apart, a plurality of transportable reinforced concrete slabs arranged in abutting relation transversely of the frame members to constitute the wall of the bin, said slabs being provided with a series of metallic bars arranged end to end lengthwise of the units, with the ends of the bars bent and all disposed toward one of the sides of the slabs, said bars being of a length substantially equal to the distance intervening adjacent frame members, and means disposed through the slabs whereby the latter are removably secured to the frame members.
2. In a coaling station provided with a hopper or bin comprising a supporting structure composed of wooden frame members arranged in spaced relation at the bottom and sides of the hopper, a plurality of transportable reinforced concrete planks of

uniform dimensions arranged in abutting relation transversely of the supporting frame members, the edges of said planks being formed to provide compact joints between adjacent planks, and means whereby the planks may be removably secured to the supporting frame members.

3. A coaling station provided with a hopper or bin comprising a supporting structure composed of wooden frame members arranged in spaced relation at the bottom and sides of the hopper, a plurality of reinforced concrete planks or slabs, of transportable and uniform dimensions arranged in abutting relation transversely of the supporting frame members, the edges of the planks being formed to provide self-setting or self-forming moisture-shedding joints, and means whereby the planks may be removably secured to the supporting frame members.

WALTER T. KRAUSCH.
